FIRE EXTINGUISHER

Michael J. Sullivan, New York, N. Y.

Application March 17, 1942, Serial No. 435,086

1 Claim. (Cl. 299—131)

The present invention relates to new and useful improvements in fire fighting equipment and has for its primary object to provide a spray head adapted for attaching to the end of a fire hose and designed for projection downwardly into an opening in a roof, floor, pier, deck of a ship, or other surface for suspending the spray head into a room or compartment or below the floor of a dock or pier, whereby to direct a spray of water for extinguishing a fire without necessitating the entrance of the firemen into the affected area.

A further object of the present invention is to provide a fire extinguisher of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the spray head in suspended position through an opening in a structure and with parts shown in section.

Figure 2 is a sectional view through the spray head taken substantially on a line 2—2 of Figure 1.

Figure 3 is a fragmentary sectional view through the coupling for the supply pipe.

Figure 4 is a longitudinal sectional view through one of the adjustable nozzles.

Figure 5 is a transverse sectional view through the supply pipe and showing the detachable collar for retaining the spray head in the opening of the structure.

Figure 6 is a bottom plan view of the cover plate for the opening in the structure after the spray head has been removed.

Figure 7 is a sectional view through the opening in the structure and showing the cover plate in position therein.

Figure 8 is a side elevational view of the spray head in diagram illustrating the angle of discharge of the adjustable nozzles carried in the casing of the spray head, and

Figure 9 is a similar view of a spray head designed for use under a wharf, pier or the like.

Referring now to the drawings in detail, wherein for the purpose of illustration I have disclosed a preferred embodiment of the invention, the numeral 5 designates a spray head gen-

erally, which is of substantially cylindrical form and rounded at each end to close the same, the spray head being composed of upper and lower sections 6 and 7 connected together by flanges 8 and 9 through which bolts 10 are inserted. In the bottom of the lower section 7 is a drain plug 11 and projecting upwardly from the top of the upper section 6 is a pipe 12 for connecting with a section of a fire pipe 13 by means of a conventional form of pipe coupling 14. The pipe section 13 is intended to be inserted through an opening 15 formed in a floor 16, or other structure, the pipe above the floor having handles 17 formed thereon and adapted for connection with a fire hose 18 by means of an elbow 19 so that the spray head 5 may be suspended in a room or other area beneath the floor 6.

The sections 6 and 7 of the spray head 5 are formed with a plurality of flared openings 20, which are internally threaded at their inner ends for threadedly receiving nozzles 21, which project inwardly of the spray head 5.

The nozzles 21 include tubular members 22 internally threaded at their inner ends, as shown at 23, for threadedly receiving a funnel-shaped member 24 secured in adjusted position with respect to the tubular member 22 by means of a set screw 25. The connected end of the funnel member 24 is provided with a spider 26 from which a valve stem 27 projects into the tubular member 22, the outer end of the tubular member 22 being flared as shown at 28 to form a valve seat for the head 29 formed on the outer end of the stem 27.

The nozzles 21, formed of the tubular members 22 and the funnel members 24, are arranged in spaced relation throughout the entire areas of the sections 6 and 7 of the spray head 5 and are inclined, in a manner as illustrated in Figure 8 of the drawings, so that the water will be sprayed from the nozzle 5 in all directions.

In order to prevent the pressure of water from raising the spray head upwardly through the opening 15, I provide a sectional collar 30 adapted for securing in position on the pipe section 13 by means of fastening members 31 and adapted to engage under a plate 32 covering the opening 15 and spray head to move upwardly through the action of the pressure of the water.

After the fire has been extinguished the opening 15 may be closed by means of a cover plate 33 having a lug 34 on its under surface to prevent displacement of the cover plate being formed with a recess 35 having a handle 36 extending transversely thereof to facilitate removing of the cover

plate when it is desired to insert the spray head through the floor.

In Figure 8 of the drawings the discharge nozzles 22 are shown inclined downwardly adjacent the lower end of the spray head and are inclined upwardly adjacent the top thereof to direct the water in all directions in a room or component in which the fire is located. In Figure 9 the spray head is designed for use under wharves, piers, and the like and the nozzles are inclined upwardly to direct the water against the underside of the floor of the wharf.

It is believed the details of construction, advantages and manner of use of the device will be

readily understood from the foregoing without further detailed explanation.

Having thus described the invention what I claim is:

5 A spray nozzle comprising a tubular member adapted for attaching to a hollow body with one end of the member projecting into the body, a flared extension adjustably connected to the inner end of the member, said member having a flared 10 valve seat at its outer end, and a valve carried by the extension for axial movement in the member into and out of engagement with the valve seat.

MICHAEL J. SULLIVAN.
